UNITED STATES PATENT OFFICE.

HARRY M. WEBER, OF BLOOMFIELD, NEW JERSEY, ASSIGNOR TO ELLIS-FOSTER COMPANY, A CORPORATION OF NEW JERSEY.

SAPONIFIED COMPOSITION.

No Drawing.

Application filed October 4, 1920, Serial No. 414,616. Renewed March 6, 1926.

This invention relates to a process of making a saponified product containing unsaponified oil adapted for use as a shampoo cream or paste and relates in particular to 5 a product containing saponified cocoanut or palm kernel oil incorporated with unsaponified oil in such a manner as to produce a substantially smooth paste having free lathering properties.

10 In the preparation of soaps intended for shampoo purposes it has been proposed in the past to completely saponify an oil such as cocoanut oil and make a solution of such saponified product either aqueous or alcoholic to yield a preparation which is placed 15 on the market for shampooing purposes. Such products oftentimes contain excess alkali which has injurious effects and they are also bulky due to the large amount of water 20 or other solvent employed. In the present invention it is particularly the object to produce a highly concentrated shampooing material which will have no objectionable amounts of free alkali and which will have 25 a tendency to leave in the scalp a beneficial amount of a vegetable or mineral oil. The product also may be suitably medicated if desired and likewise suitably perfumed but in the present invention it is especially an 30 object to carry out the process under conditions which will afford a composition that has a pleasing odor in itself or one which has no objectionable odor but has an odor indicative of the origin of the oil employed, 35 thus the use of strong perfumes to cover up the odor of ill smelling oils or rancid soaps is avoided and a product obtained which will immediately indicate to the user the nature of the materials employed and also that 40 they have been derived in a cleanly manner without rancid conditions.

The basis of the lathering component of my composition is preferably cocoanut oil. This when saponified has remarkable lathering 45 properties and such oil together with palm kernel oil have lathering qualities greatly superior to the other common saponification oils. The preparation of cocoanut oil soap which has no objectionable odor is 50 however not an easy matter. Cocoanut oil as obtained is often rancid and in boiling down with alkali to make a soap further rancidification may occur. Also if any unsaponified cocoanut or similar kind of oil is 55 present during the drying out process em-

ployed in the preferred form of my invention, an additional rancidification may take place imparting a very undesirable odor to the soap. Furthermore it is preferable to have the soap practically free from free alkali so that the only alkali developed in use is substantially that produced by hydrolysis of the soap. In order to produce a substantially neutral product I prefer to proceed in the following manner. The cocoanut oil is 60 saponified with an excess of alkali preferably caustic soda when a hard soap is desired. In some cases for particularly soft preparations caustic potash may be employed but in the preferred embodiment of the invention caustic soda is the alkali used. The cocoanut oil may be saponified as stated with an excess of caustic soda, using sufficient water, boiling being continued until the oil is as nearly completely saponified as possible. 65 It may then be salted out by the addition of brine and the soap precipitate thus obtained re-dissolved and again precipitated by the addition of brine or salt. The product then is practically free from free alkali and may 70 be dried. Preferably a temperature of 75 100-110° C. is employed in drying the soap. 80

As ordinarily prepared from the grades of cocoanut oil available the dried product will have an odor slightly to strongly rancid 85 and if the product is incorporated with sweet vegetable oil (i. e. vegetable oil substantially free from acidity) under these conditions the latter may have imparted to it an objectionable odor. In order to remove 90 the hydrocarbons, aldehydes or other bodies giving this rancid odor the dried soap may be washed with a solvent for these bodies (for example ether) which removes all such rancid smell and gives a white powder practically 95 free from odor and which may be incorporated with the oil without sacrificing the odor of the latter.

Powder so obtained is then mixed with the oily base, the latter being a clean peanut 100 oil, well refined cocoanut oil, olive oil, or similar vegetable oil or it may be petroleum oil of a refined character such for example as white mineral oil or Russian mineral oil, petrolatum or purified soft greasy material 105 from mineral oil. Preferably the composition contains a greater proportion of the soap than the oil. Oils such as here mentioned are liquid or of a soft consistency, and are hereinafter referred to as "soft oil" 110

as distinguishing from normally hard and solid oils. The oils above mentioned are substantially stable when exposed to the atmosphere, as distinguished from strongly 5 drying oils, turpentine, etc., which oxidize or thicken rapidly under such conditions. I seek to produce a product having powerful lathering properties and containing only a moderate amount of the healing or medicat- 10 ing oil. Hence a major proportion of the soap powder is used, preferably two to three parts of the powder to one part of the oil. This is preferably ground with the oil until 15 a smooth paste results, depending on the consistency of the oil. The proportion of the latter may be varied according to conditions. Enough soap is preferably used to afford a paste which holds its consistency well without separation of oil from the solid 20 soap. Hence an oil of the nature of Russian petroleum oil requires a greater amount of the soap powder to produce such a paste than does an oil of more consistent character such as cocoanut oil. Grinding the dry soap 25 powder with the oil in this manner appears to be a highly useful step in producing a composition of the desired consistency, as it not only enables the use of a lesser amount of oil but also affords a composition from which 30 the oil component does not run or separate in an objectionable manner.

As an illustration of the manner in which the process of the present invention may be carried out and a desirable product produced 35 the following is given:

50 parts by weight of cocoanut oil was saponified with 12.5 parts by weight of caustic soda. The caustic soda was first dissolved in sufficient water to make a 20% 40 solution. The saponification was started by diluting a portion (say half) of the 20% solution with double its volume of water, heating the dilute caustic soda solution to the boiling point and the cocoanut oil was 45 then added slowly. After saponification had started the rest of the alkali in the form of a strong 20% solution of caustic soda was gradually added, while maintaining the solution at the boiling point. When the saponification 50 was complete the soap formed was salted out by means of a strong salt brine. The soap was separated from the spent lye and brine solution. It was then redissolved in boiling water and again thrown out of 55 solution by means of a strong salt brine. The soap was then dried at 100-110° C. until the product crumbled readily on crushing. The soap was then ground to pass a 50 mesh screen and was then extracted in 60 the cold with ether. The soap product obtained was a white odorless powder.

24 parts by weight of the above soap stock (i. e., the purified white soap) was then ground with 14 parts by weight of a highly 65 refined cocoanut oil until a smooth creamy

paste was obtained. There was no difference in the odor of the shampoo paste formed and the odor of the original highly refined cocoanut oil. The product obtained was 70 eminently suited for purposes of shampoo- ing.

While I have mentioned ether as an extraction medium to remove rancid material I may also use other volatile solvents which do not dissolve soap readily and which do 75 not leave any objectionable odor in the product as for example well rectified carbon bisulphide or benzol may be used.

In carrying out the foregoing operations I prefer to obtain an anhydrous product or 80 one that is practically free from moisture especially when the oil employed is of vegetable origin. For example cocoanut oil directly obtained from the fresh fruit has a 85 very pleasing cocoanut oil odor which is quickly destroyed in contact with moisture or alkali. Therefore in order to preserve this odor for a considerable time at least I prefer to have the oil dry and the deodorized soap powder free from moisture. To this end 90 strong drying should be resorted to, to give a well desiccated product.

The term "soap" as used herein is intended to be restricted to the alkali metal salts of the fatty acids, prepared for example by saponifying a fat with an alkali. It is not intended to employ this term to embrace fatty acid salts nor resin acid salts of the alkaline earth metals, such alkaline earth metal compounds being generally insoluble in water. It is furthermore not intended to cover in this specification compositions in which resin acids are used in large amounts (i. e. in amount equal to or in excess of the amount of fatty matter) in preparing 100 the soap.

What I claim is:—

1. The process of making a shampoo composition which comprises saponifying cocoanut oil with an excess of caustic soda, salting out to separate the soap from free alkali, drying and extracting with a solvent capable of removing rancid material, eliminating the solvent and grinding the product with a minor proportion of an oil vehicle to produce a paste. 115

2. A process of making a composition suitable as a shampoo in the form of a creamy mixture, which comprises the step of mixing together substantially anhydrous 120 water-soluble soap substantially free from rancid constituents commonly present in cheap soaps, with a dry non-rancid clean-smelling vegetable fatty oil substantially stable in the atmosphere, in such proportions 125 as to form a creamy mass, the mixing being conducted so as to produce a substantially uniform mixture.

3. A process of making a shampoo material which comprises mixing together 130

thoroughly dry water-soluble soap substantially free from rancid constituents commonly present in cheap soaps, from which the odoriferous compounds have been removed, together with a clean highly refined, dry non-rancid oil substantially stable in the atmosphere, the mixing being so conducted as to produce a substantially uniform mixture of said materials.

10. 4. A shampoo composition, comprising a liquid to pasty mass comprising a minor proportion of a liquid vegetable oil vehicle of pleasing natural odor which is substantially stable when exposed to the atmosphere, incorporated with a major proportion of a substantially neutral dry water-soluble soap, free from the rancid odor normally present in soaps made from somewhat rancid grease.

HARRY M. WEBER.
